UNITED STATES PATENT OFFICE.

JAMES H. NUTTER, OF ERLANGER, KENTUCKY.

BURNER.

Application filed March 12, 1925. Serial No. 15,083.

My invention relates to gaseous or liquid fuel burners, and more especially to burners designed to vaporize the heavier liquid fuels, such as kerosene, burning the vapor as thus generated.

The object of my invention is to, in general, improve the operation and simplify the construction of burners of that character; especially to obtain thorough vaporization without overheating, and to provide a thorough mixture of air with the vapor and obtain an effective distribution of the flame with a minimum of deterioration of the burner structure. A further object is to provide for economy of manufacture of such burners, and to simplify the use thereof to make them readily adaptable to domestic use, whether for cooking stoves or ranges, or for heating stoves or furnaces. Other objects will appear in the course of the ensuing description.

I attain these objects by the device illustrated, for example, in the accompanying drawings, in which

Figure 1 is a plan view of a burner embodying my invention, of a design suitable for use in a cooking stove or range;

Fig. 2 is a vertical-sectional side elevation of the same, the section being on the plane of the line 2—2 of Fig. 4;

Fig. 3 is a bottom plan view of the same;

Fig. 4 is a front end elevation of the same;

Fig. 5 is a detail front end elevation of the mixer damper;

Fig. 6 is a vertical longitudinal section, enlarged, on the plane of the line 6—6 of Fig. 4;

Fig. 7 is a vertical cross-section, on the same scale, on the planes of the line 7—7 of Fig. 6;

Fig. 8 is a similar cross-section on the plane of the line 8—8 of Fig. 6;

Fig. 9 is a sectional detail, corresponding to the section of Fig. 6, further enlarged, better to show the valve construction;

Fig. 10 is a vertical cross-section on the plane of the line 10—10 of Fig. 9;

Fig. 11 is a plan view, corresponding to Fig. 1, but showing a modification of the burner, adapting it for use in a heating stove or furnace, the view being partly in horizontal cross-section on the plane of the line 11—11 of Fig. 12;

Fig. 12 is an end elevation of this modified burner;

Fig. 13 is a vertical cross-section on the plane of the line 13—13 of Fig. 11, of one of the segments of the modified burner; and

Fig. 14 is a partial side elevation of the modified burner, looking to the right in the region of the sectional illustration in Fig. 11, better disclosing the formation of the main part of the burner where it joins one of the segments, the adjoining segment being omitted.

In the example of Figs. 1 to 10, inclusive, the main body part of the burner, which may be an iron or steel casting, comprises the lower distributing head 1 at the rear end, opening upwardly into the rear ends of parallel laterally spaced distributing ducts 2 and 3, which are closed at their front ends; the plugs 4 screwed into the front ends being merely the closures of core-support openings incident to casting the body part, the other opening for which is the inlet opening 5 in the front wall of the distributing head, at its middle, below the space between the two ducts 2 and 3. The top of the head 1 is closed between the ducts, and at the rear end, extending across this space from duct to duct, is the web 6 having a half-circular upwardly opening recess 7 in its upper edge midway between the ducts. Also, at the front ends these ducts 2 and 3 are joined by a web 8 having its top edge below the tops of the ducts. The structure just described preferably is formed in one integral casting.

Each one of the ducts 2 and 3, approximately of rectangular cross-section, but preferably having their upper adjacent corners 9 amply rounded, has a series of transverse slots 10 cut in its top and extending for some distance down into the upright sides. Preferably, these slots 10 are deeper at the inner adjacent sides than at the outer sides, as best seen in Fig. 7. The slots 10 are very narrow in proportion to the other dimensions of the ducts; for example, about one thirty-second inch wide in a burner for a range or cooking stove or the like of usual size. In practice, these slots may be cut by a gang of slitting saws on a milling machine or the like, with great economy of labor, as well as of equipment.

The front plate 11 has its upper narrower part screwed to the front web 8 of the body

part, and projects down even with the bottom of the rear head 1 thereof; thus forming, with the head 1, the bottom of the device, to rest on suitable supports in the stove, 5 range or the like in which the burner is used. At its middle, below the ducts 2 and 3, this plate 11 has the opening 12, and on its inner or rear face it has the bead 13 extending around concentric with the opening 12, except at the bottom, where the bead is discontinued. Also, the middle of the bottom edge of the plate 11 is recessed, and a boss 14 formed thereon below the opening 12 has a set screw 15 threaded up through it into 10 the opening 12. This opening is alined with the opening 5 of the head 1.

The mixing chamber 16 is tubular, extending parallel with the ducts 2 and 3, with its front end held inside the bead 13 and its 20 rear end against the front of the distributing head 1 with the interior of the chamber 16 registering with the opening 5 in the head. Ears 17 project from opposite sides of the rear end of the chamber 16 and are screwed 25 to the front wall of the head 1. The lower side of the front end part of this mixing chamber is omitted, leaving the air inlet 18. Along the top of this tubular chamber 16 is the trough 19, projecting slightly up 30 between the ducts 2 and 3 and adapted to hold a strip 20 of absorbent material, such as wicking. The damper 21 is a shell, cylindrical except that its top is omitted, and with open ends; thus fitting around the tubular 35 chamber 16 from one side of the trough 19 to the other, and adapted to be slid forward or backward therealong, to cover the air inlet 18 more or less completely. The handle rod 22 extends back through an opening in 40 the front plate 11, at one side, and has its rear end fixed to a laterally extending lug 23 on the front end of the damper 21; thus serving for adjusting this damper from in front of the device.

45 The vaporizer or generator comprises the tube or pipe 24 resting, near its rear end, in the recess 7 and having its rear end entering the fuel-supply head 25, up into the bottom of which head leads the nipple 26, behind 50 the rear web 6 of the burner body part. This vaporizer tube 24 extends forward parallel with and partly down in the space between the burner ducts 2 and 3, over the absorbent strip 20. At the front of the device the tube 55 24 curves down over and in front of the plate 11, and has on its lower end the valve body 27 which has a rearwardly projecting nozzle 28 extending through and snugly fitting in the opening 12 of the front plate 11 and 60 thus forming the front support for the vaporizer or generator.

This valve body 27 also has the bottom downwardly projected neck 29, and has an upright passage 30, approximately of the 65 same diameter as the interior of the vapo-

rizer tube 24, from the lower end of this tube 24 out through the bottom neck 29; being closed by a cap 31 screwed on the exterior of the neck 29, with a suitable gasket 32. Also, the valve body 27 has the forward- 70 ly projected front neck 33, and has a transverse passage 34 through this neck 33 into the upright passage 30, alined with a transverse passage 35 from the upright passage 30 back into the nozzle 28, through the rear end of which this passage 35 has a much reduced outlet 36 surrounded interiorly by the conical valve seat 37 (Fig. 10.) The passage 35 is threaded for part of its length, and the valve rod 38, projecting back 75 through and snugly fitting in the front passage 34, projects into the rear passage 35, with threads 39 engaging the threads of the passage. Behind these threads 39 the rod is reduced, forming a neck 40, succeeding 80 which the rod is somewhat enlarged, forming the valve-plug part 41, the front end of which is conical to fit the seat 37, with the needle 42 projecting back from its center into the reduced outlet 36. This rod 38 85 also has the longitudinal groove 43 cutting through its threads 39, and long enough to form a passage from the upright valve body passage 30 back into the annular space within the rear passage 35 around the rod neck 40; and the plug part 41 is small enough to leave an annular outlet there-around to the reduced outlet 36 when the rod is screwed 90 forward, with the needle 42 more or less closing this outlet as the rod is screwed backward and forward. A cap 44, screwed 95 on the exterior of the front neck 33, compresses packing 45 against the end of the neck around the valve rod 38, which rod has at its front end a suitable handle 46 for 100 turning it.

In the modification of Figs. 11 to 13, inclusive, the structure so far described is retained; the modification consisting in providing the outer sides of the ducts 2' and 3' 110 with ports 47 and 48 near the front and rear ends, respectively, of the device, and mounting upon the sides the additional ducts, each in three sections or segments 49, arranged in series from the front ports 47 outward and then inward to the rear ports 48; making the general contour of the entire device approximately octagonal, with all of the sections 49 alike in shape. Each section has 115 top ears 50 and bottom ears 51 at its ends, by which the sections are bolted together and to the top ears 52 and bottom ears 53 on the main ducts 2' and 3'. Each section 49 is straight, with its slots 10' cut across its top, similarly to the cutting of the main ducts 2' and 3'. Such a design thus permits 120 of economy in manufacture, as a number of the extension duct sections may be cut at one time.

125 In arranging the vaporizing receptacle, 130

constituted by the tube 24, the mixing chamber 16 and the outlet ducts 2 and 3, all in juxtaposition and parallel to each other, I am enabled to provide a burner of large capacity within a relatively small space and with a relatively small amount of material in its construction. By having the mixing chamber 16 below the outlet ducts 2 and 3, and leading the mixture upward therefrom to the ducts through the head 1, from the air inlet 18, the natural draft due to the pressure of the cooler atmosphere on the mixer contents, warmed by the admixture of the heated vapor from the receptacle 24, promotes the flow from mixer to outlet ducts. By disposing the outlet ducts 2 and 3 in flanking relation to the vaporizing tube or receptacle 24, with the receptacle in the plane of the duct outlet areas represented by the duct slots 10, the heating effect of the flames from the slots 10 is sufficient for vaporizing, yet not so great as to cause overheating and pre-ignition within the mixer 16. The slots 10 being cut deeper on the sides of the ducts next to the vaporizer 24, the flames are directed slightly toward the vaporizer, insuring the above effect. Exclusion of duct outlet area from under the vaporizer 24 not only eliminates the tendency to overheating; it permits the wicking or the like, 20, in the trough 19, to be directly under the vaporizing receptacle or tube 24 where, saturated with a convenient inflammable liquid, such as alcohol, for example, it can act effectively as a preheater for the receptacle 24, when starting operation of the burner, before the flame from the outlet ducts 2 and 3 can be utilized for that purpose. Further, location of the mixer below the outlet ducts 2 and 3 avoids overheating of the mixer 16, as occurs with a mixer up over or in substantially the plane of the outlet ducts. The vapor generated in the tube 24 has to travel downward to the mixer 16; but it is under pressure from the source of liquid-fuel supply, so that it travels downward without difficulty.

The valve body 27 having the bottom adapted to be opened by removal of the cap 31, below the valve-controlled passage 35, allows solid particles coming in with the fuel to fall into the lower interior space thus defined, instead of being forced into the valve controlled passage 35, where they would get between the valve-plug part 41 and its seat 37, preventing sufficient closure of the valve to reduce the vapor outlet for correct operation. By removal of the cap 31 from time to time, particles thus collecting may be cleaned from the device. The valve rod 38, having the longitudinal groove 43 through its threads 39, has these threads of ample bearing area on the threads of the passage, so as to be firmly supported in accurate relation to the seat 37 and outlet ori-

fice 36; yet this passage 43 is of ample capacity to supply the vapor past the threads 39 to the orifice 36. The front plate 11, forming at once the front support for the ducts 2 and 3, and for the vaporizing receptacle 24 and the mixer damper rod 22, permits a very simple and compact construction; especially as to the receptacle or tube 24, which is held in place by the set screw 15 clamping its nozzle 28 in the opening 12 of the plate 11, and only rests its rear end part in the recess 7 of the burner body part, so that this vaporizer, together with its valve device, can be assembled apart from the other heavier and less delicate parts of the burner and then assembled as a whole with those parts in a very simple manner. And of course it may be taken off, for repairs or replacement, in an equally convenient manner. It will be seen that the mixer damper 21 is firmly guided in its embracing relation to the mixer tube 16; and permits a wide range of adjustment of air supply, from practically complete closure to complete opening of the air inlet 18, by means of a very simple, direct and easily understood manipulating means at the front of the burner.

Modifications other than those herein exemplified may occur in practice. Therefore, while I have explicitly described certain preferred construction and arrangement of parts herein, I do not wish to be understood as being limited to such precise disclosure, but having thus fully described my invention as is required, what I claim as new and desire to secure by Letters Patent is:

1. In a burner, a body comprising parallel laterally spaced distributing ducts closed at their front ends and a distributing head integral with the lower parts of the rear ends of said ducts, into which said ducts open downwardly, having an opening in its front below said ducts, said ducts having slots cut transversely in their tops, down into their lateral sides, a plate secured to said front ends of said ducts, depending therefrom and having an opening therebelow, a mixing chamber held between said plate and said head, in communication with the openings therein, and having a lateral air inlet, and a vaporizing tube having its rear end supported on said head, extending along over the space between said ducts and curving down into said opening in said plate.

2. In a burner, a body comprising parallel laterally spaced distributing ducts closed at their front ends and having a web integrally joining the lower parts of their front ends and a distributing head integrally joining the lower parts of their rear ends, into which head said ducts open downwardly, said head having on its top an integral upstanding web integrally joining said ducts and having an opening in its front below the

space between said ducts, said ducts having therein, and having a lateral air inlet, and slots cut transversely in their tops, down into their lateral sides, a plate secured to said front web and depending therefrom and having an opening therebelow, a mixing chamber held between said plate and said head, in communication with the openings

a vaporizing tube having its rear end supported on said rear web, extending along over the space between said ducts and curving down into said opening in said plate. 10

JAMES H. NUTTER.
